UNITED STATES PATENT OFFICE

TODD P. WILLIAMS, OF HOUSTON, TEXAS, ASSIGNOR TO TEXAS IRON WORKS SALES CORPORATION, A CORPORATION OF TEXAS

TONGS

Application filed March 6, 1930. Serial No. 433,834.

This invention relates to new and useful improvements in a tong.

One object of the invention is to provide a tong especially adapted for use in making up, or screwing together, the sections of a drill stem, or other pipe, as the same is being lowered into a well bore, and for breaking out said sections as the drill stem or pipe is being withdrawn from the bore, and the invention comprises, in particular, means incorporated into the tong for causing said tong to engage the pipe, or a coupling, or tool joint thereof, in such manner that the tong will not readily be displaced from the pipe while in use but may be readily removed therefrom when desired.

With the above and other objects in view, this invention has particular relation to certain novel features of construction, operation and arrangement of parts examples of which are described in this specification and illustrated in the accompanying drawings wherein:

Figure 1 shows a bottom plan view of a type of tong, commonly known as a breakout tong, embodying the invention.

Figure 2 shows a sectional view thereof, taken on the line 2—2 of Figure 1.

Figure 3 shows an edge view of the tong.

Figure 4 shows a plan view of a tubing tong, embodying the invention, as applied to a tubing, said view showing also a back up tong as applied to a coupling of said tubing.

Figure 5 shows a vertical sectional view of the tubing and the tongs applied thereto, as shown in Figure 4, taken on the line 5—5 of said Figure 4, and

Figure 6 shows a plan view of a back up tong, embodying the invention, as applied to a pipe.

Referring now more particularly to the drawings, wherein like numerals of reference designate similar parts in each of the figures the numeral 1 designates a tong handle whose operative end 2 is beveled and provided with an engaging jaw 3 preferably detachable. There is a clamp 4, articulate in form, one end of which has spaced fingers 5—5 which embrace the handle 1 and are connected thereto by the pivot pin 6.

This clamp 4 has the opposing, inside, flanges 7, 7, whose inner, or free, margins are preferably parallel. These free margins are spaced apart a distance such that the pipe or stem 8 will fit snugly between them and when the tong is applied to said pipe, above the tool joint, or other coupling, 9, and moved downwardly the flanges 7 will rest on the upper end of such tool joint. The inner side, or face 10, of the clamp, describes more than one half of a circle of such diameter that said face 10 will fit closely around said tool joint and consequently the clamp can not slip off of the tool joint laterally, but the tong must be elevated until the clamp clears the upper end of the tool joint before the tong can be removed. This construction of the clamp will prevent the displacement of the tong from the pipe until it is desired to remove the same.

The inner face, or side, 10 of the clamp 4 has the engaging jaws 11, 11, adapted to engage the tool joint 9 and, in cooperation with the jaw 3, to turn the upper member of the tool joint, when the tong is appropriately manipulated, and to thus break the joint, while the lower section of the tool joint is held stationary by means of a back up tong in the well known manner.

In Figures 4 and 5 there is illustrated a tubing tong embodying the same principle, as hereinabove explained. This type of tubing tong has been particularly designed for application to tubing having upset, or outwardly thickened ends. This type of tong also embodies the handle 1, substantially similar in all respects to that of the tong shown in Figures 1 to 3. In this form the clamp 4' is elongated each way beyond the handle and is provided at one side with the spaced fingers 5', 5' which embrace the handle and are connected thereto by the pivot 6' and within the elongated clamp 4' are the engaging jaws 11', 11' adapted to engage the tubing. The ends of the clamp are flared forming the inside faces 10' which extend more than half way around. This type of tong is particularly adapted for use on tubing having upset ends, as above explained, said tubing being designated by the numeral 100.

8' and the up-set end thereof being indicated by the numeral 12. The end of the tubing adjacent the coupling 13, is usually gradually thickened and flared externally. When 5 the tong is applied to the tubing above the thickened portion 12 thereof it may be then gradually lowered until the flared lower face 10' seats on the externally flared portion 12 of the tubing and the face 10' describing more 10 than one half a circle will lock on the flared portion 12 to prevent the tubing from being detached from the tubing accidentally or until it is lifted upwardly to clear the flared portion 12. This type of tong may be reversed and, as is obvious, may be used for 15 screwing the sections together or unscrewing them.

The back up tong shown in Figure 6 embodies the same principle as that of the break out tong disclosed in Figure 1, having the handle 14 with the beveled operating end 15 and the pipe engaging jaw 16 at said operating end. In this type of tong there is 20 the arcuate clamp 17 pivotally and adjustably attached to said handle. The clamp 17 has the opposing inside flanges 18, 18 whose inner or free margins are parallel. These free margins are spaced apart a distance such that the pipe or stem will fit snugly between 25 them and when the tong is applied to said pipe above the tool joint, or coupling, and moved downwardly the flanges 18 will rest upon the upper end of such tool joint or coupling. The inner side or face 19 of the 30 clamp describes more than one half of a circle of such diameter that said face 19 will fit closely around the tool joint or coupling, and consequently the clamp can not slip off of 35 said joint or coupling laterally but the tong must be elevated until the clamp clears the tool joint or coupling before the tong can be removed. This clamp 17 may be provided with the engaging jaws 20, 20 which 40 will cooperate with the handle jaw 16 causing the tong to securely engage the pipe or coupling, as shown in Figures 4 and 5. This back up tong is applied to the coupling 45 as 13 so as to hold the same while the section of pipe above is being unscrewed. While 50 so applied, the pivot 21 on which the clamp 17 operates will work through the bearing 22 of the handle 14. As shown in Figure 6, however, the back up tong is applied to the pipe beneath the coupling so as to hold the 55 pipe against turning while a section above is being screwed into the coupling 13 when the pipe is being made up. The back up tong is applied to the pipe rather than to the coupling, during this operation so that when 60 the section above is screwed home in the coupling, said coupling, if loose on the section beneath, will be free to be tightened up. While thus used, the pivot pin 21 should 65 be inserted through the bearing 23 of the handle 14 so as to adjust the jaw 16 further

inwardly toward the jaws 20, 20 to the end that said jaws will be in proper position to engage the pipe beneath the coupling or tool joint, connecting the sections of pipe.

The drawings and description disclose 70 what is now considered to be preferred forms of the invention by way of illustration, while the broad principle of the invention will be defined by the appended claims.

What I claim is:—

1. A tong for pipe, and the like, having external couplings and including a handle whose operative end is adapted to engage the pipe to be turned, an arcuate clamp open at one side to receive, and formed to surround, 80 the pipe and one end of which is pivoted to said handle, an inside projection carried by said clamp forming a support to rest on said coupling, an inside arcuate bearing in said clamp which describes more than one half 85 of a circle and which is of a diameter greater than the outside diameter of the pipe and approximately the same as that of a coupling so as to fit closely about the coupling.

2. A tong for pipe, and the like, having 90 external couplings of greater diameter than the pipe, said tong including a handle having an operative end to engage the object to be turned, an arcuate clamp open at one side to receive a pipe and one end of which is pivoted 95 to the handle, said clamp having a minimum inside diameter less than the outside diameter of a coupling, and said clamp also having an inside, arcuate, bearing which describes more than one half of a circle and which is of a 100 diameter substantially equal to the outside diameter of said coupling.

3. A tong including a handle, an arcuate clamp pivoted to the handle adjacent the operative end thereof and one side of which is 105 open and thus adapted to receive and surround an object to be turned, said clamp having an inside arcuate bearing which describes, substantially, more than one half of a circle, and said clamp adjacent said bearing being 110 contracted and thus having a smaller inside diameter than that of said bearing.

4. A tong including a handle, an arcuate clamp, open at one side and pivoted to the handle and adapted to receive and surround 115 an object to be turned, said clamp having an inside arcuate bearing which describes, substantially more than one half of a circle, said clamp being contracted, inwardly, adjacent said bearing.

5. A tong including a handle, an arcuate clamp pivoted to the handle and having a side opening and adapted to surround an object to be turned, said clamp having an inside arcuate bearing which describes, substantially more than one half of a circle, 125 said clamp being contracted, inwardly, adjacent said bearing and engaging jaws in said bearings and at the operative end of the handle.

6. A tong including a handle, an arcuate clamp, having a side opening, pivoted to the handle and adapted to surround an object to be turned, said clamp having an inside arcuate bearing which describes, substantially, more than one half of a circle, said clamp being contracted, inwardly, adjacent said bearing and being adjustable on the handle.

7. A tong including a handle having engaging means at one end thereof, a clamp, having a side opening, and pivotally connected to the handle and having an arcuate inside face which, substantially, describes more than one half of a circle, said inside of said clamp being contracted, adjacent said inside face.

In testimony whereof I have signed my name to this specification.

TODD P. WILLIAMS.
